PAINT BRUSH WRAPPER
Cye E. Saunders, 50-45 230th St., Bayside, N.Y.
Filed Oct. 30, 1962, Ser. No. 234,165
11 Claims. (Cl. 206—15.1)

The present invention relates to a paint brush wrapper. More particularly, the invention relates to a wrapper for the bristles of a paint brush which covers said bristles and holds and supports the paint brush.

The principal object of the present invention is to provide a new and improved paint brush wrapper.

An object of the present invention is to provide a paint brush wrapper which covers and protects the bristles of a brush.

Another object of the present invention is to provide a paint brush wrapper which covers and protects the bristles of a brush and holds and supports the brush at the same time.

Another object of the present invention is to provide a paint brush wrapper which is facilely and effectively applied to a brush and which is facilely and effectively removed from the brush.

Still another object of the present invention is to provide a paint brush warpper which covers and protects the bristles of brushes of different sizes and shapes and holds and supports a brush at the same time that it protects its bristles.

In order that the present invention may be readily carried into effect, it will now be described with reference to the accompanying drawings, wherein:

FIG. 1 is a front view of an embodiment of the paint brush wrapper of the present invention;

FIG. 2 is a front view of the embodiment of FIG. 1 applied to a paint brush;

FIG. 3 is a side sectioned view of the paint brush wrapper and paint brush of FIG. 2 taken along the lines III—III of FIG. 2;

FIG. 4 is a front view of another embodiment of the paint brush wrapper of the present invention; and

FIG. 5 is a front view of the embodiment of FIG. 4 applied to a paint brush.

In the figures the same components are identified by the same reference numerals.

In FIGS. 1, 2 and 3 an enveope 11 has two sides 12 and 13. The envelope 11 is preferably of plastic material and in a preferred embodiment of the invention is of clear plastic material. The envelope 11 is of substantially rectangular configuration and has four edges 14, 15, 16 and 17. The sides 12 and 13 of the envelope 11 are therefore of substantially rectangular configuration and are joined to each other along their edges 14, 15, 16 and 17 to form the envelope.

The edges 14 and 16 are opposite and substantially parallel to each other and the edges 15 and 17 are opposite and substantially parallel to each other. The edges 14 and 15, the edges 15 and 16, the edges 16 and 17 and the edges 17 and 14 are at substantially right angles to each other.

A first opening 18 is formed in the envelope 11 along a first one of the edges, such as, for example, the edge 14. The first opening 18 extends along substantially the entire length of the edge 14 and is therefore of sufficient length to admit the bristles 19 of a brush having bristles 19 and a handle 20, the bristles extending in the longitudinal direction of the handle. The brush may of course be any type of brush, such as, for example, a paint brush, a paste brush, a pastry brush, although it is referred to as a paint brush.

A second opening 21 is formed in the envelope 11 along a second one of the edges, such as, for example, the

2

edge 15. The second opening 21 extends for a fraction of the length of the first opening 18 and is adapted to admit the handle 20 of the brush. The length of the second opening 21 is merely sufficient to admit the handle 20 of the brush and is too short to permit passage of the bristles 19 of the brush therethrough.

In the embodiment of FIG. 1, the second opening 21 is formed along the edge 15 which is at substantially right angles to the edge 14 along which the first opening 18 is formed.

A flap 22 is integrally formed with the envelope 11 and extends from the side 13 thereof along the edge 14 and is adapted to fold along the edge 14 to close the first opening 18. A snap fastener is utilized to secure the flap 22 to the side 12 of the envelope 11 in its closed position, although any suitable fastening means may be utilized. The fastener comprises a first part 23 affixed to the flap 22 and a second part 24 affixed to the side 12 of the envelope 11. The first and second parts 23 and 24 of the fastener cooperate with each other when pressed together to hold the flap closed over the first opening 18.

An aperture 25 is formed through the sides 12 and 13 of the envelope 11 in proximity with the edge 17 in the embodiment of FIG. 1. The aperture 25 may have a seam or lip 26 provided around it and joining the sides 12 and 13 of the envelope to each other. The aperture 25 permits the brush wrapper of the present invention to be hung on an elongated object, such as a nail, and supported thereby.

The envelope 11 may be formed of a single sheet of plastic material folded together along its edges, or it may be formed of two sheets of plastic material joined together along their edges. In either case, the flap 22 extends from and is integrally formed with a sheet of plastic material. Even if the envelope 11 is formed of a single sheet of material, it may be seamed along its edges in order to maintain its shape and to strengthen it.

The brush wrapper of FIG. 1 is used by opening the flap 22 so that the first opening 18 is unobstructed. The brush is then inserted into the envelope 11 through the first opening 18, handle first. The handle 20 of the brush is passed through the first opening 18, through the envelope 11 and through the second opening 21 to the outside of said envelope. After the handle 20 of the brush extends through the second opening 21 to the outside of the envelope 11, the bristles 19 of the brush have passed through the first opening 18 and are enclosed by said envelope. The flap 22 is then closed over the first opening 18 and fastened to the side 12 of the envelope 11, as shown in FIGS. 2 and 3. The envelope 11, with the brush in it, may then be hung on a convenient nail or peg or the sort so that the brush is supported and held at the same time that its bristles are protected.

Any size or shape of brush may be protected by the brush wrapper of the present invention as long as the second opening 21 is long enough to admit the handle of the brush and too short to permit the bristles of the brush to pass through it.

To remove the brush from the wrapper, it is necessary merely to open the fastener 23, 24, open the flap 22, and pass the brush through the first opening 18, bristles first.

In FIGS. 4 and 5, an envelope 11' has two sides 12' and 13' and is preferably of clear plastic material, as the embodiment of FIG. 1. The envelope 11' is of substantially rectangular configuration and has four edges 14', 15', 16' and 17', as the embodiment of FIG. 1. The sides 12' and 13' of the envelope 11' are therefore of substantially rectangular configuration and are joined to each other along their edges 14', 15', 16' and 17' to form the envelope.

The edges have the same relationship toward each other as those of the embodiment of FIG. 1.

A first opening 31 is formed in the envelope 11' along a first one of the edges, such as, for example, the edge 17'. The first opening 31 extends along substantially the entire length of the edge 17' and is therefore of sufficient length to admit the bristles 19' of a brush having bristles 19' and a handle 20', the bristles extending in the longitudinal direction of the handle.

A second opening 21' is formed in the envelope 11' along a second one of the edges, such as, for example, the edge 15'. The second opening 21' extends for a fraction of the length of the first opening 31 and is adapted to admit the handle 20' of the brush. The length of the second opening 21' is, as in the embodiment of FIG. 1, merely sufficient to admit the handle 20' of the brush and is too short to permit passage of the bristles 19' of the brush therethrough.

In the embodiment of FIG. 4, contrary to that of FIG. 1, the second opening 21' is formed along the edge 15' which is opposite and substantially parallel to the edge 17' along which the first opening 31 is formed.

A flap 32 is integrally formed with the envelope 11' and extends from the side 13' thereof along the edge 17' and is adapted to fold along the edge 17' to close the first opening 31. A snap fastener is utilized to secure the flap 32 to the side 12' of the envelope 11' in its closed position, although, as in the embodiment of FIG. 1, any suitable fastening means may be utilized. The fastener comprises a first part 33 affixed to the flap 32 and a second part 34 affixed to the side 12' of the envelope 11'. The first and second parts 33 and 34 of the fastener cooperate with each other when pressed together to hold the flap closed over the first opening 31.

An aperture 35 is formed through the sides 12' and 13' of the envelope 11' in proximity with the edge 17' and through the flap 32 in proximity with said edge in the embodiment of FIG. 4. The apertures 35, 36 permit the brush wrapper of the present invention to be hung on an elongated object, such as a nail, and supported thereby.

The envelope 11' may be formed as the envelope 11 and may be seamed as the envelope 11.

The brush wrapper of FIG. 4 is used by opening the flap 32 so that the first opening 31 is unobstructed. The brush is inserted into the envelope 11' through the first opening 31, handle first. The handle 20' of the brush is passed through the first opening 31, through the envelope 11' and through the second opening 21' to the outside of said envelope. After the handle 20' of the brush extends through the second opening 21' to the outside of the envelope 11', the bristles 19' of the brush have passed through the first opening 31 and are enclosed by said envelope. The flap 32 is then closed over the first opening 31 and fastened to the side 12' of the envelope 11'. The brush is then securely covered by and protected in the envelope 11', as shown in FIG. 5. When the flap 32 is fastened to the side 12' of the envelope, the aperture 36 through the flap coincides with the aperture 35 through the sides 12' and 13' of the envelope, as shown in FIG. 5. The envelope 11' with the brush in it, may then be hung in the manner of the embodiment of FIG. 1.

Any size or shape of brush may be protected by the brush wrapper of the present invention as long as the second opening 21' is long enough to admit the handle of the brush and too short to permit the bristles of the brush to pass through it.

To remove the brush from the wrapper, it is necessary merely to open the fastener 33, 34, open the flap 32, and pass the brush through the first opening 31, bristles first.

While the invention has been described by means of a specific example and in specific embodiments, it is not wished to be limited thereto, for obvious modifications will occur to those skilled in the art without departing from the spirit and scope of the invention.

What is claimed is:

1. A wrapper for the bristles of a brush having a handle and bristles extending in the longitudinal direction of said handle, comprising an envelope having two sides and a plurality of edges, a first opening formed in said envelope along a first one of said edges adapted to admit the bristles of said brush and a second opening integrally formed in said envelope along a second one of said edges and smaller than said brush width and adapted to admit the handle of said brush; a flap integrally formed with said envelope extending from a first one of the sides thereof along said first one of said edges to close said first opening; an aperture formed through the sides of said envelope in proximity with an edge of said envelope opposite said second edge of said envelope and at a point beyond the extending bristles of said brush for supportingly hanging said envelope; and fastening means having first and second cooperating parts, the first part of said fastening means being affixed to said flap and the second part of said fastening means being affixed to the second one of the sides of said envelope.

2. A wrapper for the bristles of a brush having a handle and bristles extending in the longitudinal direction of said handle, comprising an envelope of plastic material having two sides and a plurality of edges, a first opening formed in said envelope along a first one of said edges adapted to admit the bristles of said brush and a second opening integrally formed in said envelope along a second one of said edges and smaller than said brush width and adapted to admit the handle of said brush; a flap integrally formed with said envelope extending from a first one of the sides thereof along said first one of said edges and adapted to fold along said first one of said edges to close said first opening; an aperture formed through the sides of said envelope in proximity with an edge of said envelope opposite said second edge of said envelope and at a point beyond the extending bristles of said brush for supportingly hanging said envelope; and snap fastening means having first and second cooperating parts, the first part of said fastening means being affixed to said flap and the second part of said fastening means being affixed to the second one of the sides of said envelope.

3. A wrapper for the bristles of a brush having a handle and bristles extending in the longitudinal direction of said handle, comprising an envelope of substantially rectangular configuration having two sides and four edges, a first opening formed in said envelope along a first one of said edges adapted to admit the bristles of said brush and a second opening integrally formed in said envelope along a second one of said edges at substantially right angles to said first one of said edges and smaller than said brush width and adapted to admit the handle of said brush; a flap integrally formed with said envelope extending from a first one of the sides thereof along said first one of said edges and adapted to fold along said first one of said edges to close said first opening; an aperture formed through the sides of said envelope in proximity with an edge of said envelope opposite said second edge of said envelope and at a point beyond the extending bristles of said brush for supportingly hanging said envelope; and fastening means having first and second cooperating parts, the first part of said fastening means being affixed to said flap and the second part of said fastening means being affixed to the second one of the sides of said envelope.

4. A wrapper for the bristles of a brush having a handle and bristles extending in the longitudinal direction of said handle, comprising an envelope of substantially rectangular configuration having two sides and four edges, a first opening formed in said envelope along a first one of said edges adapted to admit the bristles of said brush and a second opening integrally formed in said envelope along a second one of said edges opposite and substantially parallel to said first one of said edges and smaller than said brush width and adapted to admit the handle of said brush; a flap integrally formed with said envelope extend-

first and second cooperating parts, the first part of said fastening means being affixed to said flap and the second part of said fastening means being affixed to the second one of the sides of said envelope.

11. A wrapper for the bristles of a brush having a handle and bristles extending in the longitudinal direction of said handle, comprising an envelope of clear plastic material of substantially rectangular configuration having two sides and four edges, a first opening formed in said envelope along a first one of said edges extending along substantially the entire length of said first one of said edges adapted to admit the bristles of said brush and a second opening integrally formed in said envelope along a second one of said edges opposite and substantially parallel to said first one of said edges and smaller than said brush width and adapted to admit the handle of said brush, said second opening extending for a fraction of the length of said first opening; a flap integrally formed with said envelope extending from a first one of the sides thereof along said first one of said edges and adapted to fold along said first one of said edges to close said first

opening; an aperture formed through the sides of said envelope in proximity with an edge of said envelope opposite said second edge of said envelope and at a point beyond the extending bristles of said brush for supportingly hanging said envelope; and fastening means having first and second cooperating parts, the first part of said fastening means being affixed to said flap and the second part of said fastening means being affixed to the second one of the sides of said envelope.
